METHOD FOR VAPORIZING LIQUEFIED
PETROLEUM GASJames Woodward Martin, Dallas, Tex., assignor
to Lone Star Gas Company, Dallas Tex., a cor-
poration of Texas

Application April 30, 1935, Serial No. 19,114

8 Claims. (Cl. 48—211)

My invention consists in new and useful improvements in a method and apparatus for converting liquid hydrocarbons, such for example as liquefied petroleum gases, into a gas for use as domestic and industrial fuel, the present application being a continuation in part of my pending application Serial No. 731,231, filed June 19, 1934.

As in my former application, the object of the present invention is to provide a method of vaporizing substantially pure butane and analogous liquefied petroleum gases wherein the rate of vaporization of the liquid is automatically controlled by the rate of consumption of the gas formed.

It has long been known that various hydrocarbons may be stored in the liquid state and used as fuel upon vaporization. It has likewise been known that the latent heat of vaporization of the particular hydrocarbon used must be supplied to the liquid hydrocarbon during the conversion of the latter into the vapor state. Hydrocarbons such as propane which will vaporize at very low temperatures and therefore more readily absorb the heat required for vaporization from the atmosphere through the walls of the storage containers, have long been used as fuel in liquid gas systems. However, such hydrocarbons are rather expensive and difficult to obtain in large quantities and the expense of handling these hydrocarbons in the liquid phase is a considerable item because of their very high vapor pressures at normal atmospheric temperatures, which requires heavy and expensive equipment to retain and transport the liquid.

Hydrocarbons having lower vapor pressures such as butane are not only more plentiful and cheaper to produce in a state of satisfactory purity, but they may be stored as liquids in cheaper, lighter equipment. However, although such hydrocarbons as butane vaporize under substantially atmospheric pressure, at temperatures which approach atmospheric temperature, the latent heat of vaporization of such hydrocarbons which must be supplied to convert the liquid into a vapor cannot be absorbed from the atmosphere under all conditions but must be supplied by auxiliary means.

My present invention, as that covered in my co-pending application, relates to an improved method and apparatus for supplying the required heat of vaporization to liquid hydrocarbons particularly of this character.

I am familiar with various methods heretofore employed for applying heat to liquid hydrocar-

bons for vaporizing the same. For example, this has been effected by exposing the container in which the hydrocarbon is stored, to the atmosphere or to the ground, in some climates the atmospheric temperatures or ground temperatures being sufficiently high to produce the required amount of heat to vaporize the liquid hydrocarbon where comparatively low rates of evaporation are required and during at least a few months of the year. Naturally by this procedure there is no insurance of uniformity in the production of gas for fuel use.

In some instances the liquid hydrocarbon has been exposed directly to a liquid of low volatility and of low solubility in the hydrocarbon, most commonly water, the heating liquid having a temperature higher than the boiling point of the hydrocarbon, in which case the transfer of heat is made directly from the heating liquid to the hydrocarbon. Also hydrocarbons have been exposed indirectly to another liquid such as water while said hydrocarbons were contained in storage vessels, the water having a temperature higher than the boiling point of the hydrocarbons and being caused to flow over the hydrocarbon container or through a tube or coil submerged in the hydrocarbon, whereby the heat of the water is transferred to the hydrocarbon indirectly through the walls of the container or the tubes.

In still other instances, steam has been employed for indirectly heating liquid hydrocarbons while the latter are confined in storage vessels, and in some instances the heat required to generate the steam or to heat the heating liquid has been derived from the combustion of a portion of the hydrocarbon vapors formed.

In all of these former methods however, the thermal efficiency has been low and the cost of operation high.

It is the primary object of my invention to overcome the difficulties and disadvantages inherent in the processes and apparatus heretofore employed, and to this end I apply the heat produced by the combustion of a portion of the hydrocarbon vapor formed in the process, to the liquid hydrocarbon while the latter is confined within a storage container without the necessity of employing steam, water or other auxiliary heating fluids which increase the cost of operation and reduce the thermal efficiency of the operation.

Another object of my invention is to provide automatic means controlled by the pressure in the hydrocarbon container for regulating the

heat applied to the liquid therein, thus automatically controlling the pressure in the container within the desired limits.

Another object of the present invention is to provide means for revaporizing any vapors condensed after leaving the storage receptacle, thus preventing the distribution piping from becoming filled with liquid formed by condensation.

With my improved process, I maintain a pressure inside the storage container sufficient to provide an adequate supply of vapor to the point of utilization by maintaining the entire volume of stored liquid hydrocarbon at such temperature as will produce and maintain under service conditions an adequate vapor pressure. I permit the hydrocarbon to pass from the storage container for purposes of utilization only as a dry vapor of which there is a constant ready supply regardless of atmospheric or ground conditions.

With the above and other objects in view which will appear as the description proceeds, my invention consists in the novel features herein set forth, illustrated in the accompanying drawing and more particularly pointed out in the appended claims.

Referring to the drawing in which numerals of like character designate similar parts throughout both views,

Fig. 1 is a vertical sectional view showing a storage container equipped with one form of heating means similar to that covered in my co-pending application hereinbefore mentioned, and

Fig. 2 is a similar view showing a modified form of heating means.

Both of these figures illustrate my improved revaporizing conduit.

In the drawing, 1 represents a suitable storage vessel preferably insulated to reduce to a practical minimum the transfer of heat between the container and the atmosphere. 2 is an inlet connection located at any suitable point in the wall of the container and through which the supply of liquefied petroleum gas is charged to the receptacle, said connection being provided with any conventional valve means. In the top wall of the container 1, I provide a valved vapor outlet 3 to which is connected a vapor line 4, the latter having interposed therein a conventional gas regulator 5 for maintaining on the service line 6 a reasonably constant pressure of any desired value less than the pressure in the storage container.

Referring to Fig. 1, 7 represents a gas burner of any suitable type located in substantially close proximity to a portion of the bottom wall of the container 1, said burner being fed by a branch line 8 leading from the service line 6 and provided with a valve 9. The flow of gas through line 8 to the burner 7 is automatically controlled by a pressure actuated valve 10 which is responsive to the pressure in the vapor space above the liquid in container 1, by means of a conduit 11 connected to the vapor line 4 at a point anterior to the regulator 5.

A second branch line 12 leads from branch line 8 to a pilot 13 immediately adjacent the burner 7, the flow of gas to said pilot being controlled by a suitable valve 14.

Directly above the burner 7 is the mouth 15 of a heat transfer element 16 which consists of a tubular conduit extending vertically for a short distance through the bottom wall of the receptacle 1 into the liquid in said receptacle and then downwardly at an incline, the end of said inclined portion extending out into the re-

ceptacle through the lower extremity of its side wall as at 17.

Any suitable means for housing the burner 7 and eliminating drafts may be employed, such for example as that forming the subject matter of my co-pending application Serial No. 19,115 filed of even date herewith.

The service line 6 extends downwardly from vapor line 4 adjacent the wall of container 1, its lower extremity terminating in communication with a curved conduit 6' which extends through the walls of the receptacle 1 adjacent the lower portion thereof and is submerged in the liquid contained in the receptacle. The discharge end of conduit 6' projects through the opposite wall of the receptacle where it is adapted to be connected to the distributing system of a house or other place of utilization.

In the top wall of the receptacle 1, I preferably install a pressure relief valve 18 to prevent excessive pressures in the storage receptacle by exhausting the high pressure vapors to the atmosphere when the pressure in the receptacle reaches a predetermined amount. A gauging device 19 arranged adjacent the wall of the receptacle permits ready determination of the liquid content so that the liquid may be replenished before the supply in the storage receptacle becomes exhausted.

Referring to Fig. 2, it will be noted that all of the details of structure are identical with those just described with the exception that instead of the submerged heat transfer element 16, in the modified form I provide a coil 20 which is connected to the side wall of the storage receptacle 1. A burner 1a is located directly beneath the lower extremity of the coil 20 and is fed by pipe 8a from the service line 6. Pilot 13a is located immediately adjacent the burner 1a and is fed by pipe 12a branching off of pipe 8a.

Having thus described the construction of apparatus by means of which my improved method may be carried out, its operation is as follows:

Referring to Fig. 1, liquid butane or the like is introduced into the tank or receptacle 1 through the valved inlet 2, leaving a vapor space above the liquid level, which space becomes filled with hydrocarbon gas. Naturally, if this gas or vapor is to be used as fuel in any ordinary type of gas burner, the pressure in the hydrocarbon storage receptacle must be somewhat greater than atmospheric pressure, so that the vapor will flow from the tank to the burner, and under some conditions, for example in warm weather, sufficient heat is absorbed from the atmosphere to supply the necessary vapor pressure, and the vapors formed in the space above the liquid level in tank 1 will be discharged through vapor line 4, service line 6 and conduit 6' to the point of utilization.

However, under other conditions, for example in cold weather, or when the tank 1 is subjected to any atmospheric conditions which will not supply the necessary heat for vaporization, artificial heating means is necessary. Under these conditions, the pilot 13 is lighted after first opening valves 9 and 14, the main burner 7 being normally shut off by pressure control valve 10, when the vapor pressure in tank 1 is above a predetermined value.

Now then, the removal of vapor from the tank through the service line will cause a slight decrease in pressure in the tank which decrease in pressure will allow some of the liquid fuel to evaporate to form a vapor which naturally con-

sumes a certain quantity of heat. Thus the removal of vapor from the tank causes a decrease in the temperature of the liquid in the tank, and as the liquid becomes cooler, its vapor pressure in turn decreases.

When the vapor pressure in the tank has fallen below a predetermined value, the pressure controlled valve 10 opens in response and permits the flow of gas from the service line 6 through pipe 8 to the burner 7 which is ignited by the pilot 13. The products of combustion from the burner 7 pass upwardly through the mouth 15 of the heat transfer element 16 and are discharged at the outlet end 17 of the latter. The heat transfer element 16 being submerged in the liquid in the bottom of tank 1 raises the temperature of said liquid and in turn increases the vapor pressure in the space above the liquid, and after this vapor pressure has been brought up to the proper value, the valve 10 automatically shuts off the supply of gas to the burner 7, the pilot remaining lighted.

It will be noted that the angle of inclination of the major portion of the heat transfer line 16 permits any water of condensation to drain towards the discharge end, thus conducting any moisture away from the burner.

This intermittent operation of the burner 7 maintains the mass of liquid in the container at a substantially uniform temperature throughout. Any condensate in the distributing lines connected to the discharge end of conduit 6' flows back by gravity to the lowest point in said conduit and is immediately revaporized due to the heat exchange between the liquid hydrocarbon in the container and the conduit 6'. As before stated, this conduit 6' is located in the lower part of the storage receptacle so that even when the liquid in the receptacle is at a low level, this desired heat exchange is effected.

By laying the distribution or house piping (not shown) to grade so that the lowermost point in the curved conduit 6' is the lowest point in the entire vapor line, any condensed vapors that may form in the house piping will flow towards this low point and upon reaching that portion of the conduit which is submerged in the storage container will become re-heated, and if condensation of vapors in the house piping reaches the liquefaction state, such liquid will become revaporized upon reaching conduit 6'. Thus by re-heating or revaporizing these vapors before passing into the house piping, a more uniform vapor temperature and burner performance is insured.

The operation of the modified form of my invention shown in Fig. 2 embodies the same principle as that just described. However, instead of heating the liquid by passing the products of combustion through a conduit submerged in said liquid, in the modified form the heat is applied by burner 1a to the coil 30, vaporizing the liquid in the coil and causing a circulation from the tank through the coil and back to the tank. This circulation gradually heats the entire body of liquid in the receptacle to a sufficient degree to maintain the required vapor pressure for distribution of the fuel through the service system. The automatic control and the re-heating or revaporizing features in the modified form are identical with those heretofore described.

It will thus be seen that I have provided an improved method and apparatus which may be readily and economically employed in connection with distribution systems for liquefied petroleum gases to insure at all times a ready and

constant supply of fuel vapor. The fuel consumed by the heating burner and the pilot is only a fraction of the total fuel vaporized, and under normal conditions will not amount to over one percent (1%) of the total fuel vapor formed.

From the foregoing it is believed that my invention may be readily understood by those skilled in the art without further description, it being borne in mind that numerous changes may be made in the details disclosed without departing from the spirit of my invention as set forth in the following claims. For example, although I have described two forms of apparatus by means of which my method may be carried out and have referred particularly to butane, it is to be understood that the practice of the invention is neither limited to apparatus shown and described nor to the use of butane. Obviously this invention may be practiced with any of the liquefied petroleum gases.

What I claim and desire to secure by Letters Patent is:—

1. A method for converting liquefied petroleum gas into vapor for use as fuel, consisting in maintaining a body of the liquid in a storage zone, maintaining a vapor space above the level of said liquid, conducting heated products of combustion of a portion of the effluent vapors into close proximity with said body of liquid but out of contact therewith to vaporize the same, and maintaining the vapors thereby formed in a vapor state by conducting said vapors through said heated body of liquid but out of contact therewith.

2. A method of converting liquefied petroleum gases into a gas for use as fuel, consisting in maintaining a bulk supply of the liquid in a storage zone, maintaining a vapor space above the level of said liquid, vaporizing a portion of said liquid, burning a portion only of the vapors formed, heating said bulk supply by directing the products of said combustion through a passageway submerged in the liquid confined in said storage zone, and conducting the remainder of said vapors through a passageway submerged in the liquid confined in said storage zone, thus utilizing the heat contained in said liquid for maintaining said vapors in a vapor state.

3. A method of converting liquefied petroleum gases into a gas for use as fuel, consisting in maintaining a bulk supply of the liquid in a storage zone, maintaining a vapor space above the level of said liquid, vaporizing a portion of said liquid, constantly burning a predetermined minimum portion of the vapors formed, increasing the portion of the vapors burned as required to maintain a predetermined pressure in said storage zone, controlling the increased flow of vapors above the predetermined minimum required, by the vapor pressure in said zone, and heating said bulk supply by directing the products of said combustion through a passageway submerged in the liquid confined in said storage zone.

4. A method of converting liquefied petroleum gases into gas for use as fuel, consisting in maintaining a bulk supply of the liquid in a storage zone, maintaining a vapor space above the level of said liquid, vaporizing a portion of said liquid, burning a portion only of the vapors formed, in close proximity to the liquid in said zone, heating said bulk supply by the heat of said combustion while the liquid is confined in said storage zone, and conducting the remainder of said vapors through a passageway submerged in the liquid in

said zone, thus utilizing the heat contained in said liquid for maintaining said vapors in a vapor state.

5. A method of converting liquefied petroleum gases into gas for use as fuel, consisting in maintaining a bulk supply of the liquid in a storage zone, vaporizing a portion of said liquid, burning a portion of the vapors formed, and conducting a restricted stream of said liquid from said bulk supply, through the products of combustion from said burning step, but out of contact therewith, and back to said bulk supply to heat the latter.

6. A method as claimed in claim 5 wherein the remainder of said vapors formed in said storage zone are conducted through a passageway submerged in the liquid in said zone, thus utilizing the heat contained in said liquid for maintaining said vapors in a vapor state.

7. A method of converting liquefied petroleum gases into a gas for use as fuel, consisting in

maintaining a body of the liquid in a storage zone, maintaining a vapor space above the level of said liquid, vaporizing a portion of said liquid within said zone, conducting said vapors from said zone through a passageway, splitting said vapors into two streams, burning the vapors of one stream at a point in close proximity to the lower extremity of said storage zone thereby forming hot products of combustion, conducting the vapors of the other stream to a point of utilization, and heating said body of liquid by directing said products of combustion through a passageway submerged in the liquid confined in said storage zone.

8. The method as claimed in claim 7 wherein the supply of said vapors to be burned in said first stream is automatically controlled by the pressure conditions existing in said storage zone.

JAMES WOODWARD MARTIN. 20
